Term of patent 14 years

Int. Cl. D12—14

U.S. Cl. D90—20

FIG. 2.

FIG. 3.

FIG. 1 is a perspective view of a pneumatic tire embodying our new design, it being understood that the rib segments are of a color contrasting with the color of the background of the sidewall.

FIG. 2 is an elevational view, to a reduced scale, of the tire design of FIG. 1; and

FIG. 3 is a fragmentary sectional view, to an enlarged scale, of a tire cross section, taken substantially on the plane indicated by the line 3—3 of FIG. 1.

The sidewall opposite to the one shown is the same except that the raised rib segments are omitted.

The characteristic feature of our design resides in the sidewall shown.

We claim:

The ornamental design for a pneumatic tire, substantially as shown and described.
